UNITED STATES PATENT OFFICE.

CHARLES T. CARSON, OF SEATTLE, WASHINGTON.

SALMON-SLIMING MACHINE.

1,109,039.

Specification of Letters Patent. Patented Sept. 1, 1914.

Application filed January 31, 1914. Serial No. 815,704.

To all whom it may concern:

Be it known that I, CHARLES T. CARSON, a citizen of the United States of America, residing at Seattle, in the county of King 5 and State of Washington, have invented certain new and useful Improvements in Salmon-Sliming machines, of which the following is a specification, reference being had therein to the accompanying drawing.

10 This invention relates to fish cleaning machines, and has especially for its object the production of an efficient salmon sliming machine which will efficiently clean the salmon without the necessity of employing 15 a number of workmen to handle the same.

Another object of the invention is the production of a simple and efficient means for feeding the fish along the body of the cleaning or sliming machine so as to cause 20 the fish to be readily cleaned.

With these and other objects in view this invention consists of certain novel combinations, constructions, and arrangements of parts as will be hereinafter fully described 25 and claimed.

In the accompanying drawings:—Figure 1 is a top plan view of the machine. Fig. 2 is a central longitudinal section through the machine. Fig. 3 is a transverse section 30 through the machine taken on line 3—3, of Fig. 2. Fig. 4 is an end view of the discharge end of the machine. Fig. 5 is a side elevation of the machine. Fig. 6 is a detail perspective view of the hinge portion of the 35 hood of the machine. Fig. 7 is a section taken on line 7—7, of Fig. 2. Fig. 8 is a transverse sectional view through one of the sections of the clamping hood illustrated in Fig. 6. Fig. 9 is a side elevation of one of 40 the cleaning wheels. Fig. 10 is a vertical section through one of the cleaning wheels illustrated in Fig. 9. Fig. 11 is a section taken on line x—x of Fig. 1.

By referring to the drawings it will be 45 seen that 1 designates the frame which is supported upon the usual legs 2, and this frame 1 supports a substantially inverted V-shape top 3 which is provided with laterally extending sides 4 and a sheet metal 50 hood 5 is placed over the top 3 as indicated clearly in Figs. 2 and 3. It will be seen that this hood 5 will constitute means for holding the fish against displacement from the top 3 as the fish are being passed longitudinally of the machine. The hood 5 is 55 kept in firm engagement with the fish pass-

ing between the top 3 and the hood 5 by means of the tension springs 6 which are mounted upon the bolts 7, and these springs 6 engage the upper faces of the side portions 8 of the hood 5, thereby keeping a tension 60 upon the hood 5 but yet allowing sufficient movement to permit the passing of different size fish through the machine.

A plurality of bearings 9 are formed integral upon the frame 1 and detachable sections 10 of these bearings are secured to the bearing portions 9 for firmly holding the transverse shafts 11 upon the frame 1 of the machine. A plurality of these shafts 11 are 70 employed preferably five in number, and upon the first shaft and intermediate its ends is keyed a feeding wheel 12 which feeding wheel is provided with a plurality of spurs 13, which are preferably six in number arranged at equal distances apart to grip the fish and force the same forwardly to be cleaned by the cleaning rollers to be hereinafter described. The top 3 is provided with apertures 14 throughout its 80 length to permit the feeding wheels 12 to pass therethrough and the cleaning wheels 15 to pass therethrough to operate upon the fish passing through the machine. The spurs 13 are, of course, of sufficient length 85 to grip the fish and force the same longitudinally of the machine. The hood 5 may be formed of any design desired and is preferably provided adjacent each cleaning wheel with a plurality of apertures 16 over 90 which apertures fits a feeding nozzle 17 carried by a feeding pipe 18 to facilitate the feeding of water to the fish to not only clean the fish but also to keep the machine free from accumulative matter. 95

The hood 5 near the entrance end of the machine is cut away as is illustrated at 19 in Fig. 2 to allow the fish to be easily placed upon the machine. In placing the fish upon the machine the fish are split longitudinally 100 and placed down upon the top 3 having the back of the fish extending upwardly and causing the fish to lie flat in a substantially inverted V-shape position upon the top 3 and extend longitudinally of the machine. The 105 fish is then moved forwardly and the spurs 13 of the feeding wheels 12 engage the backbone of the fish and force the same into engagement with the first cleaning roller 15. The water passing upon the fish and also 110 the cleaning wheel 15 will cleanse the fish to some extent and since the cleaning roller 15

will rotate the under portion of the fish will be somewhat cleaned as the fish passes longitudinally of the machine. The first shaft which supports the first feeding wheel 12 carries a large sprocket wheel 20 over which passes a sprocket chain 21, and this sprocket chain in turn passes over a smaller sprocket wheel 23 carried by the shaft which supports the first cleaning roller or brush. The gears 20 and 23 are so arranged as to cause the brush 15 to be driven at twice the rate of speed of the wheel 12, thereby facilitating the cleaning of the fish. The opposite end of the shaft which supports the gear wheel 23 carries a small sprocket wheel similar to the sprocket wheel 23 and over this sprocket wheel at the opposite end of the shaft passes a chain 24 which chain in turn passes over a sprocket wheel 25 carried by the second shaft 20 which supports the second feeding wheel 12. Preferably three of the feeding wheels 12 are mounted upon the frame 1, and two of the cleaning wheels 15 are mounted upon the frame 1. The cleaning wheels are geared to a speed of two revolutions to one revolution of the feeding wheels as previously described, and as stated above a water feed or supply may be arranged above each of the cleaning wheels.

For the purpose of thoroughly cleaning the entire inner face or inner portion of the fish a plurality of cleaning belts 26 are employed, which belts pass over a driving drum 27 and an idler drum 28. These belts 26 are of an endless belt-type, and are provided with a plurality of rubber knobs or projections which are preferably of one-eighth diameter and one-fourth in height to produce an efficient roughened surface to act upon the inner face of the fish. The belts 26 pass through the transversely extending apertures 29 sufficiently to engage the inner face of the fish, and by continually rotating the belt 26 it will be seen that the fish will be efficiently cleaned. The driving drum 27 is driven by means of a beveled gear 30 which beveled gear meshes with a gear 31 carried by the central feeding wheel supporting shaft. Both the idler drum 28 and driving drum 27 are mounted upon suitable supporting brackets suspended from the under face of the top 3. This structure is clearly illustrated in Fig. 11.

The last feeding wheel supporting shaft, or in other words the shaft which is at the discharge end of the machine carries a driving sprocket 32 over which a driving sprocket chain 33 passes, and this chain also passes over a sprocket wheel 34 driven by the power shaft 35. The power may be imparted to the shaft 35 by any suitable means passing over the wheel 36.

The hood 5 is provided near the delivery or discharge end of the machine with an aperture 37, and within this aperture 37 is

mounted a hinge back clamp 38. This back clamp 38 carries a hinge 39 which is hingedly secured to the hood 5 by means of a pin 40. The hinge back 38 comprises a pair of sections which are connected to the hinge 39 to allow the free movement of these sections independently. The sections of the back clamp 38 are provided with an inner lining 41 which comprises a plurality of projecting portions 42 adapted to be clamped upon or held in engagement with the back of the fish for removing the scales therefrom as the fish are drawn under the sections of the back clamp 38 by means of the last feeding wheel 12 illustrated clearly in Fig. 2. Brackets 43 are carried by the hood 5 and straddle the respective sections of the back clamp 38 and are provided with a plurality of apertures, through which apertures extend the bolt portions 44 of the back clamp 38. These bolt portions 44 carry coil springs 45 which normally exert a downward pressure upon the back clamp 38, and nuts 46 are threaded upon the outer ends of the bolts 44 so as to limit the inward swing of the back clamp 38 upon the top 3.

The cleaning wheels 15 are provided with laterally extending collar portions 47 which are adapted to fit snugly upon the shafts adapted to support the same and a rubber covering 48 is mounted upon the cleaning wheels 15 and comprises a plurality of projecting knobs similar in construction to those referred to in connection with the back clamp illustrated clearly in Fig. 6.

By referring to Fig. 8 it will be seen that the inner lining 41 of the back clamp comprises a rubber sheet having the knobs 42 formed thereon, and this sheet is held in engagement with the body of the back by means of substantially T-shape rubber knobs 49.

Having thus described the invention what is claimed as new, is:—

1. A machine of the class described comprising a frame, a top, a hood positioned upon said top, said top provided with a plurality of apertures, feeding wheels extending through said apertures, cleaning wheels extending through some of said apertures, and means for yieldably holding said hood upon said top.

2. A machine of the class described comprising a frame, a substantially inverted V-shape top provided with a plurality of aligned apertures, feeding wheels extending through some of said apertures, cleaning wheels extending through other of said apertures, a shield hood positioned over said top, means for yieldably supporting said shield hood upon said top, and means for feeding water to said hood.

3. A machine of the class described comprising a frame, a top, a hood yieldably supported upon said top, feeding wheels ex-

- tending through said top and adapted to feed fish longitudinally of said top as said feeding wheels are rotated, cleaning wheels supported adjacent said feeding wheels and 5 adapted to travel at a greater rate of speed than said feeding wheels, and means for feeding water under said hood.
4. A machine of the class described comprising a frame, a top supported thereon, feeding and cleaning wheels supported in alined relation upon said top and frame, a hood fitting over said top, means for feeding water to said top, and transversely extending cleaning belts carried by said top 15 adapted to efficiently clean the under face of fish adapted to pass thereover.
5. A machine of the class described comprising a frame, a top carried thereby and provided with a plurality of transverse 20 apertures, cleaning belts working in said apertures, drums supporting said belts, means for driving said drums, said belts provided with roughened knobs upon their outer faces and adapted to contact with substantially the entire width of the under face 25 of a fish, means for feeding a fish longitudinally of said machine, and rotating cleaning wheels coöperating with said feeding means for engaging the central portion of the under face of a fish.
- 30 6. A machine of the class described comprising a frame, a top, a hood, said hood provided with an aperture near its discharge end, a hinge adjustable back clamp carried
- within said aperture and provided with a 35 plurality of roughened portions upon its under face, and fish feeding means rotating thereunder for drawing a fish under said clamp, whereby the scales may be efficiently removed from the back of a fish.
- 40 7. A machine of the class described comprising a frame, a top, fish cleaning means, fish feeding means, a hood positioned over said top and provided with an aperture near its discharge end, a back clamp provided with a roughened under face, brackets straddling said apertures, rods carried by said back, springs engaging said rods for exerting a downward pressure upon said back clamp, and said rods passing through 45 said brackets.
8. A machine of the class described comprising a frame, a top, a hood fitting over said top, said hood provided with an aperture, a hinge sectional back connected to 50 said hood, brackets straddling said aperture, rods carried by said back and projecting through said brackets, and springs positioned upon said rods and engaging said back for normally exerting a downward 55 pressure thereon.

In testimony whereof I hereunto affix my signature in presence of two witnesses.

CHARLES T. CARSON.
